ATTORNEY

UNITED STATES PATENT OFFICE.

GEORGES VALENTIN MARIE BERTHET, OF PARIS, FRANCE.

FOOT ARCH.

Application filed November 30, 1921. Serial No. 518,960.

To all whom it may concern:

Be it known that I, GEORGES VALENTIN MARIE BERTHET, citizen of the French Republic, residing at Paris, Department of the Seine, in France, and having P. O. address 25 Rue de la Bienfaisance, in the said city, have invented certain new and useful Improvements in Foot Arches; and I do hereby declare the following to be a full, clear, and 10 exact description of the invention, such as will enable others skilled in the art to which it appertains to make and use the same.

This invention relates to an orthopedic apparatus giving a support to the arch of a flat foot, and this in a better and more proper way than it has been done till now with the existing apparatus of this type.

The known foot-arch supports are more or less faulty in some points; if made in one piece they are resilient only longitudinally, cross way the resilience is nil. In order to make them resilient both ways it is necessary to make them in two or more pieces, they are consequently more complicated and 25 the cost of making is increased considerably. Besides most of these supports have a tendency to displace the foot from the inner side to the external one, this causes deformations and a continuous fatigue of the fifth toe.

The orthopedic apparatus made according to the invention corrects all these faults. It is resilient, both ways, and made in one piece being simple to make and consequently cheap. Besides its shape tends to displace 35 the foot towards the inside and so relieve the fifth toe.

The accompanying drawing shows:

Figure 1 a longitudinal section of an example of foot arch made according to the 40 invention.

Figure 2 a plan of same.

Figure 3 a section through the anterior part of the foot-arch on line A—A of Figure 2.

The foot-arch indicated is made for the right foot, the heel being on the left of the figure and the toes on the right.

It is made in one piece cut in a steel sheet, stamped and tempered. The arch proper is 50 shown in 1, preferably there is a rib 2 extending longitudinally of the same that tends to stiffen the arch somewhat, but

which offers no resistance to the transverse bending of the support.

On the inward side of the foot, the arch 55 extends taking the shape of a raised wing 3, this part helps to maintain the camber. The wing 3 instead of being plain as the arch, is on the contrary cut through as shewn in 4; the effect of this is to make the apparatus 60 resilient cross way. The combination of a plain arch with a wing having a hole cut through is one of the most essential features of the invention.

Another feature of the foot-arch is the 65 special stamped shape given to the anterior part of it.

It is shewn, Figures 2 and 3, that the edge 5, of the anterior part follows the shape of the line passing through the articulations of 70 the toes. An extension 6 tends to slightly raise the fifth toe, while the internal part 7 is slightly inclined downwards. The result of this special shape is to displace the foot towards the inward side and to relieve the 75 small toe.

Claims:

1. A foot-arch support formed of a single piece of spring sheet metal comprising a narrow longitudinally arched part, a broad 80 anterior part including a lateral extension on the inner side thereof and a projection on the forward outer side of the same, and a wing flared upwardly from the inner side of the arched part and to the rear of the lateral 85 extension of the anterior part.

2. A foot-arch support formed of a single piece of spring sheet metal comprising a narrow longitudinally arched part, a broad anterior part including a lateral extension 90 on the inner side thereof and a projection on the forward outer side of the same, said anterior part being slightly declined toward the side edge of the lateral extension and said projection being slightly inclined upwardly toward its forward edge, and a wing flared upwardly from the inner side of the arched part and to the rear of the lateral extension of the anterior part, the metal of the support being cut away between the arched 100 part and the wing to lessen the resistance to the bending action of the arched part.

In testimony whereof I affix my signature.

GEORGES VALENTIN MARIE BERTHET.
